UNITED STATES PATENT OFFICE.

MAXWELL ALPERN, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

STOKER.

Application filed July 24, 1920. Serial No. 398,726.

To all whom it may concern:

Be it known that I, MAXWELL ALPERN, a citizen of the United States, residing in Philadelphia, Pennsylvania, have invented 5 the Stoker, of which the following is a specification.

This invention relates to automatic stokers of the inclined underfeed type and more particularly has to do with improvements in 10 the detail construction and arrangement of the parts constituting the air box, the fuel feeding means and the mounting for the grates.

Another object of the invention is to provide 15 a novel construction and arrangement of reciprocating pushers for feeding the fuel in an automatic stoker whereby the rate at which the fuel is advanced into the furnace may be adjusted at any of a number of 20 different points between a hopper or other source of supply and the rear end of the furnace.

The invention further contemplates a 25 novel construction and arrangement of the parts of the structure for confining the air prior to its delivery to the tuyères, whereby it is possible to prevent leakage of air from said structure into the fuel hopper and a consequent blowing of gas, smoke, etc., 30 through the same into the fire room.

Another object of my invention is to provide 35 a novel means for fastening in place the extension grates as well as other associated parts of a stoker of the above type so that they may be conveniently and quickly removed or replaced.

These objects and other advantageous 40 ends I attain as hereinafter set forth, reference being had to the accompanying drawings, in which,

Fig. 1 is a plan partly in section, of an 45 automatic stoker of the inclined underfeed type embodying my invention, one series of tuyères being removed and a part of one of the retorts and a portion of its fuel feeding mechanism being shown in horizontal section taken on the line 1--1, Fig. 2 extending through one of the hydraulic cylinders;

Fig. 2 is a vertical section on the line 2--2, 50 Fig. 1;

Fig. 3 is a front elevation of the hoppers and cylinders, together with their associated parts;

Fig. 4 is a transverse vertical section on

an enlarged scale taken on the line 4--4, 55 Fig. 2;

Fig. 5 is a transverse vertical section similar to Fig. 4, taken on the line 5--5, Fig. 2;

Fig. 6 is a sectional perspective view of one of the upper secondary pushers; and 60

Figs. 7 and 8 are vertical sections on a larger scale than Fig. 2 illustrating certain details of my invention.

In the above drawings 1, 2 and 3 represent 65 relatively heavy beams or girders extending transversely of the stoker structure and having their ends suitably connected to a side frame structure, two of whose members are indicated at 4 (Fig. 3). The beams 1 and 2 are connected by a suitable number 70 of beams 5 extending between them from front to rear and serving to support the concrete or other bottom structure 6 of the wind box 7.

The furnace to which the stoker is applied 75 includes a setting or casing whose front is indicated at 8 and one of whose sides is indicated at 9, a bridge wall 10 defining the rear of said furnace. Between the front beam 1 and the front 8 of the furnace casing are mounted parallel laterally extending frame members in the shape of 80 rolled sections 11 and 12 and between the lower of these and said frame member 1 are a series of plates 13 defining the lower part 85 of the front of the stoker structure and more especially of the wind box.

Supported by the two members 11 and 12 are a series of forwardly projecting cylindrical casing structures 14 each of which has 90 opening into the top of its inner end, immediately adjacent the front face of the casing 8, a fuel hopper 15. A longitudinally movable hydraulic cylinder 16 is operative 95 within each of the casings 14 and has a fixed cooperating piston 17 connected by a rod 18 to the forward or outer end of the casing structure 14. Each cylinder 16 is also designed to serve as a ram or pusher for transferring the fuel from the hopper to its associated retort, and is movable in the casing structure 14 from a position in which its forward end is in front of the opening from the bottom of the hopper 15, to a position to the rear of said hopper.

Within the furnace chamber and extending from front to rear is mounted a series 100 of parallel beams 19 whose rear ends (Fig.

2) rest upon and are supported by the frame members 2 and whose forward ends are bolted to and carried by the inclined edges of plate brackets 20, projecting inwardly from the members 11 and 12. The brackets of each pair support and are connected by an upwardly and rearwardly inclined top plate 20^a forming with them mouth-pieces whose forward ends open into the casings 14 respectively. The beams 19 are so arranged (Figs. 4 and 5) as to define relatively narrow vertical chambers 21 constituting retorts having between them larger chambers whose lower portions form extensions of the wind box 7 while their top portions are respectively covered by downwardly and rearwardly inclined series of tuyères 22.

Plates 20^b extend transversely between the rear edges of the members 20 at the forward ends of the wind box extensions on both sides of each retort so that there is no possibility of air under pressure leaking directly from the windbox into the casings 14 or lower parts of the fuel hoppers.

Each set of tuyères is supported in a stepped series by castings 23 bolted to and rigidly connecting each pair of adjacent beams 19 which for this purpose are provided with suitable projections or flanges, and said tuyères have the usual passages or channels through which air under pressure is permitted to flow from the wind box into the furnace.

At the bottom of each set of tuyères and at the rear or inner end of each of the retorts is a line of plates 24 extending transversely of the furnace and having their top portions flush with bottom plates 25 and 26 constituting the rear end of the bottom of each retort. These plates are rigidly secured to and carried by lugs 27 projecting from the beams 19 (Fig. 4) and the rear edge or end of each of the plates 25 has the form of a recess or socket having an overhung top edge 28 and a transverse rib 29.

The various plates 24 are so formed that their forward edges are designed to fit under the overhung edges 28 of the plates 25 and they are provided with openings for the reception of keys 30 which, after said plates have been put in place as indicated in Fig. 8, may be inserted through said openings in front of the ribs 29 so as to retain each of the plates 24 in place.

The main portion of the bottom of each of the retorts is provided by one or more longitudinally movable, secondary pushers, of which in the present case there are three indicated at 32, 33, and 34, mounted one above the other in each retort. The first of these secondary pushers 32, as shown in Figs. 2 and 7, has a flat bottom forming a continuation of and at the same level as the straight transverse lip 35 projecting from

the lower portion of the rear flat face of the hydraulic plunger or ram 16 and it is movable longitudinally within the mouth piece associated with said ram, being supported and slidably on a pair of guides provided by inwardly projecting ribs 36 integral with the adjacent beams 19.

Each of these uppermost secondary pushers has sides or upwardly projecting wings 37 extending above the level of its flat bottom and beyond its rear end, which is formed with a downwardly inclined portion terminating in a vertical face, being operatively connected to its associated ram or primary pusher 16 by means of a rod 38. This is operative in a suitable groove in said ram and has on its forward end an adjustable stop 39 to provide a lost-motion-connection between said two pushers, so that the primary pusher will move forwardly in its casing for a certain part of its outward stroke before striking the stop and through the rod 38, forwardly moving the secondary pusher 32. On its inward stroke the primary pusher will similarly at first move by itself and at a certain point its lip 35 will strike and also move the secondary pusher.

The forward end of said secondary pusher rests upon or lies immediately adjacent the flat top surface of the second secondary pusher 33 and has a downwardly projecting forked lug 40 engaging a bolt 41 projecting forwardly from the forward end of said pusher 33. This bolt, like the rod 38, has an adjustable stop 42 at its forward end so that there is lost motion between said two pushers 32 and 33. The second secondary pusher 33 is slidably supported on a pair of ribs 43 projecting inwardly from the adjacent sides of the beams 19, and a third set of ribs 44 likewise serve to slidably support the third and lowest of the secondary pushers 34, whose rear end rests upon or moves immediately adjacent the top surface of the bottom plate 26 and is moved by a forked lug 45 and a bolt 46 projecting forwardly from its front end. This bolt likewise has an adjustable stop 47 whereby the lost motion between it and the pusher 33 may be adjusted.

While I have shown but three auxiliary or secondary pushers, it is obvious that more or less than this number may be employed in each retort without departing from my invention and that the amount of lost motion between each of them and between the topmost pusher 32 and the primary pusher 16, may be varied as required by the amount of fuel to be burned and by the proportion of ash in said fuel. Both the pushers 33 and 34, as well as the pusher 32, have their rear faces downwardly and rearwardly inclined as have also the forward portions of the edges of the wings or sides of said topmost secondary pusher.

Immediately to the rear of and below the line of plates 24 is a transversely extending series of stepped extension grates 50, which like the pushers and the series of tuyères, present a downwardly and rearwardly inclined face to the mass of overlying fuel. These grates are mounted upon box-like structures 55, slidably mounted on guides 53 extending at suitable intervals between the frame members 2 and 3 and each of these box members is connected through a relatively heavy rod 56 with an arm 57 bolted or otherwise rigidly connected to the lowest of the secondary pushers 34, whereby said grates are reciprocated.

Each of the rods 56 has fixed to it a pair of stops 58 between which it is engaged by the arm 57 and the position of this latter relatively to the rod is determined by a series of washers or collars 58^a inserted between it and either of the stops 58. The extension grates 50 have their forward edges downwardly flanged to loosely enter a transversely extending groove in the forward upper part of the box structure 55 wherein they are held by the overhanging portions of the plates 24. The lower and rear edge of the grates is removably locked to a rearwardly extended portion of the rear side of the box structure 55 so that it is normally held thereunto until its forward edge is raised out of its groove and the whole grate swung rearwardly around this part of the box structure as a pivot, when it is free to be lifted away from the same. For this purpose the lower end of each box structure is formed with a rearwardly projecting flange or rib 51^a and the rear edge of each grate is provided with a hook portion 50^a positioned to cooperate with said rib to normally hold said grate to the box structure.

Adjacent the rear ends of the guide members 53 are transversely extending structures 54 immediately above the frame members 3 grooved transversely of the furnace and undercut for the reception of the rearwardly turned edge of the downwardly extending flange at the front of each of a number of plates 52. When the flanges of these plates are placed in the groove of the guide members 53 and moved rearwardly as far as possible, there is left an elongated recess in which may be placed a key 59 whereby said plates are held in position.

The frame members 3 have fixed to their webs a series of rearwardly extending brackets 60 to which are pivoted dumping grates 61 whose rear edges extend immediately adjacent the bridge wall 10 where they are normally supported upon arms or dogs 62. The latter are hinged or pivotally mounted on a shaft 63 supported in bearings carried by a channel shaped casing or structure 64, preferably imbedded in the bridge wall beyond the vertical face thereof.

A handle 65 attached to this shaft makes it possible to retract the arms 62 into the member 64, thereby leaving the rear edges of the dumping grates unsupported and permitting them to drop. For raising the dumping plates and breaking or agitating the ash or clinkers thereon, I suspend from the frame members 5 a motor in the form of a cylinder 66 whose piston 67 through a rod 68 and a link 69 is connected to an arm 70 fixed to a transversely extending shaft 71. The latter is carried in bearings supported by the frame members 2 and 3 and has fixed to it any suitable number of operating arms 72, which through links 73, are pivotally connected to said dumping grates.

With the above described arrangement of parts, fuel is supplied to the hoppers 15 and fluid under pressure is delivered through suitable passages in the fixed piston rod 18 to the interior of the cylinder pusher 16. The supply and exhaust of this fluid is controlled by suitable valve mechanism (not shown) so that this ram or primary pusher is reciprocated in the casing 14. On the forward movement of the ram, fuel falls from the hopper into the forward end of the casing and as the primary pusher moves rearwardly, it forces said fuel into the mouth piece 20 and onto the topmost secondary pusher 32 which is shortly engaged by the lip 35 and is moved with said primary pusher into the retort 21.

After the secondary pusher 32 has moved rearwardly to a predetermined extent, its lug 40 comes into engagement with the second of the secondary pushers and moves this also toward the rear and it in turn, through the lug 45, engages and moves toward the rear, the lowest secondary pusher 34 with a section of the extension grate 50. After reaching the rear end of its inner stroke, fluid is exhausted from the rear end of the cavity of the primary pusher 16 and is admitted to the forward end thereof, so that said pusher moves outwardly. After completing a portion of its stroke, it engages the stop 39 of the rod 38 and moves outwardly the secondary pusher 32, which successively imparts outward movement to the two lower pushers 33 and 34 and finally to its associated section of the extension grate 50.

This reciprocation of the pushers and extension grate gradually feeds fuel from the hoppers into the retorts and insures the delivery of the ashes left after the combustion of said fuel into the pocket formed by the extension grates 50, the dumping plates 61 and the bridge wall 10, at the same time causing said grates to exert a crushing action on any clinkers of solid bodies of ash forming between them and said wall. Obviously the amount of movement imparted to the secondary pushers and extension grates may be adjusted at will by suitable

manipulation of the stops 39, 42 and 47 and also by suitable shifting of the collars or spacers 59 on the rod 56. It is thus possible to increase or diminish the rate at which 5 fuel is fed into and through the retorts and also to make provision for the proper feed and treatment of the ash accumulated in the lower and rear part of the furnace.

By having the wind box extensions defined by the beams 19 and the plates 20¹⁰ in positions removed from the front of the stoker structure, any leakage of air between these parts will take place into the retort and furnace instead of into the casings 14 and the hoppers 15, as would be the case if the air under pressure had access to points at or immediately adjacent the front of the stoker structure.

When it is desired to remove or replace 20 the extension grates 50, the key holding each of the plates 24 is first removed, thereby making it possible to move this rearwardly until the lip on its forward edge clears the rear edge of the bottom plate 25. The removal of one or more of the plates 24 thereupon uncovers the forward edge of a section 25 of an extension grate 50 which may then be removed by swinging it upwardly until its rear edge clears and may be removed from 30 engagement with the rearwardly projecting lip of the part 51 of the box structure 55.

When it is desired to remove one of the plates 52 for the purpose of taking out a dump plate, the key 59 is removed and said plate 52 is forced forwardly until its hooked edge clears the overhung edge of the casting 54. Thereupon it may be lifted out of position.

It will be noted that the air in the wind 40 box, in addition to passing into the mass of overlying fuel through the tuyère openings, may also flow from said box under the ends of the retorts into and through the space defined by the plates 24 and extension grates 50, from whence it passes into the fuel 45 through the openings between said plates and between and around the extension grates. The flow of this latter portion of the air is regulated as desired by suitable 50 rotary valves or dampers 75 mounted under the rear ends of the retorts between the rear ends of the beams 19. As shown in Fig. 5, the movable elements of these valves are connected by a series of rods 76 so that they 55 may be simultaneously adjusted to vary the flow of air as required by the greater or less amount of fuel which reaches the extension grates and the parts of the stoker adjacent thereto. Said movable elements are obviously cut away so that their movement is 60 not interfered with by the rods 56.

The frames constituting the guides 53 carry on the lower or under edges, bearings for a shaft 80 extending transversely of the 65 stoker and terminating at one side thereof

where it has fixed to it an operating arm 82. This shaft has also fixed to it a plate or series of plates 81 which in one position lie against the under side of the guide frames 53, extending between the frame members 2 70 and 3 so as to form a continuation of the wind box to supply the extension grates with air. Under conditions of use fine coal and ash work through said grates and collect in this extension wind box, and with 75 the above arrangement of parts it is possible to periodically rock the shaft 80 in its bearings by means of the handle 82 so as to swing the plate or plates 81 with a resulting discharge of the material which may 80 have accumulated. Said plates move between the frames 53 and are normally held in their closed positions shown.

I claim:—

1. The combination in an inclined under- 85 feed stoker of tuyères; retorts; a primary pusher for feeding material to each retort; and a plurality of secondary pushers mounted to constitute the bottom of each retort, one of said latter pushers being positioned 90 to be directly engaged and moved by the primary pusher when this moves in one direction.

2. The combination in an inclined under- 95 feed stoker of tuyères; retorts; a primary pusher for feeding material to each retort; a plurality of secondary pushers forming the bottom of each retort, one of said latter pushers being positioned to be directly en- 100 gaged and moved by the primary pusher when this moves in one direction; with a lost motion connection between said two lat- ter pushers.

3. The combination in an inclined under- 105 feed stoker of retorts; means for feeding fuel to and through each retort consisting of a primary pusher, a secondary pusher in the bottom of the retort positioned to be directly engaged and moved inwardly by the primary pusher; with a rod attached to one of said 110 pushers and having an adjustable lost motion connection with the other pusher.

4. The combination in an inclined under- 115 feed stoker of tuyères; retorts; with means for feeding fuel to and through each retort consisting of a primary pusher; and a plurality of superposed secondary pushers ar- 120 ranged in stepped relation and constituting the bottom of the retort, the upper second- ary pusher being positioned to be engaged and moved by the primary pusher and be- ing reciprocable immediately above the next lower secondary pusher.

5. The combination in an inclined under- 125 feed stoker of tuyères; retorts; a fuel supply casing for each retort; a fixed piston in said casing; a fuel feeding ram having a cylin- drical cavity cooperating with said piston to constitute a fluid motor; a series of opera- 130 tively connected pushers in stepped relation

forming the bottom of each retort; with means for transmitting power from the ram to the pushers including a rod having an abutment and operatively connecting one of 5 said pushers and the ram when the latter moves in one direction.

6. The combination in an inclined under-feed stoker of tuyères; a plurality of retorts; a fuel supply casing for each retort; a fixed 10 piston in said casing; a fuel feeding ram having a cylindrical cavity cooperating with said piston to constitute a fluid motor; a series of operatively connected pushers in stepped relation forming the bottom of each 15 retort; and a rod having an abutment and operatively connecting said ram and one of said pushers when the ram moves in one direction, said ram being positioned to engage and move said pusher when moved in the 20 opposite direction.

7. The combination in an inclined under-feed stoker of retorts; tuyères; and means for feeding fuel to and through each retort including a primary pusher, a series of secondary 25 pushers arranged in stepped relation and constituting the bottom of each retort, with adjustable lost motion connections between said secondary pushers, the topmost secondary pusher being positioned to be directly engaged and moved by the primary 30 pusher.

8. The combination in an inclined under-feed stoker of retorts; tuyères; and means for feeding fuel to and through each retort 35 including a primary pusher, a series of secondary pushers arranged in stepped relation and constituting the bottom of each retort, the topmost secondary pusher being positioned to be directly engaged and moved by 40 the primary pusher; with adjustable lost motion connections between said secondary pushers, and a rod having a stop and arranged to constitute a lost motion connection between the topmost secondary pusher 45 and the primary pusher.

9. The combination in an inclined under-feed stoker of retorts; means for feeding fuel to and through each retort including a primary pusher, a series of secondary 50 pushers actuated from the primary pusher and arranged in stepped relation; said secondary pushers being positioned to form the bottom of the retort and having between them lost-motion connections.

55 10. The combination in an inclined under-feed stoker of retorts; means for feeding fuel to and through each retort including a primary pusher, a series of secondary pushers actuated from the primary pusher and arranged in stepped relation; said secondary pushers being positioned to form the bottom of the retort, and a series of extension grates reciprocated from the lowest 60 secondary pushers.

65 11. The combination in an inclined under-

feed stoker of retorts; means for feeding fuel to and through each of the retorts including a primary pusher, a series of secondary pushers actuated from the primary pusher and forming the bottom of the retort, 70 and a series of extension grates reciprocated from and adjustably connected to the lowest of the secondary pushers.

12. The combination in an inclined under-feed stoker of retorts; means for delivering fuel to and through each retort consisting of a primary pusher, a series of secondary pushers arranged to constitute the bottom of each retort and actuated from the primary pusher thereof, certain of said secondary pushers having projecting lugs, with members on other pushers respectively engaging said lugs and having adjustable abutments normally arranged to constitute lost motion connections between the pushers. 80

13. The combination in an inclined under-feed stoker of a series of retorts; a series of tuyères; means for feeding fuel to and through said retorts; an extension grate adjacent the inner ends of the retorts; a series 90 of plates extending transversely of the stoker and projecting over the outer edge of the extension grate; a structure removably engaged by the inner portion of said grate and cooperating with said plates to normally hold it in position; with means for holding the plates in place.

14. The combination in an inclined underfeed stoker of series of tuyères; retorts; means for feeding fuel to and through the 100 retorts; a series of plates extending transversely of the stoker adjacent the lower ends of the retorts; means removably holding said plates in position; a reciprocable structure below said plates; with an extension 105 grate having its inner edge removably hooked to said reciprocable structure and having its outer edge extending under said plates.

15. The combination in an inclined under-feed stoker of a series of tuyères; retorts; means for feeding fuel to and through the retorts; an extension grate mounted below the retorts; a bridge wall; a series of dumping plates between the grate and the bridge 115 wall; guard plates extending over the forward edges of the dumping plates and under the extension grate; with means for removably locking said guard plates in position.

16. The combination in an inclined under-feed stoker of a series of tuyères; retorts; means for feeding fuel to and through the retorts; an extension grate mounted below the retorts; a bridge wall; a series of dumping plates between the grates and the bridge 125 wall; guard plates extending over the forward edges of the dumping plates and under the extension grate and including hooked portions; with means for removably locking said guard plates in position, the same con- 130

sisting of undercut fixed structures formed to receive the hooked portions of said guard plates, with a key normally holding said hooked portions in their engaged position.

5 17. The combination in an inclined under-feed stoker of an enclosing setting; a wind box; substantially parallel members, defining alternated retorts and wind box extensions; tuyères mounted to receive air from said extensions; means for delivering fuel to the retorts; and transverse plates cutting off the forward ends of the wind box extensions from the front of the setting.

10 18. The combination in an inclined under-feed stoker of an enclosing setting including a front plate; a wind box; pairs of plate brackets extending inwardly from the front plate; vertically set beams extending rearwardly from the brackets; plates extending 15 transversely between pairs of said beams to the rear of the front plate and coacting with the beams to define windbox extensions whose forward ends are spaced away from the front of the stoker; tuyères positioned to 20 receive air from the windbox extensions; and means for feeding fuel to and through 25 the retorts.

19. The combination in an inclined under-feed stoker of a front structure; a wind box; a structure defining alternated retorts 30 and windbox extensions, of which the latter have their forward ends spaced rearwardly away from the front structure of the stoker; and means for supplying fuel to the retorts.

5 20. The combination in an inclined under-feed stoker of a front structure; a windbox; a structure defining alternated retorts and windbox extensions of which the latter have their forward ends positioned rearwardly 35 away from the front structure of the stoker; 40 and means for supplying fuel to the retorts consisting of series of superposed secondary pushers respectively forming the bottoms of said retorts and primary pushers for respectively actuating the series of secondary 45 pushers.

21. The combination in an inclined under-feed stoker of retorts; and means for feeding fuel to and through each retort including a primary pusher and a series of movable secondary pushers forming the bottom 50 of each retort and adjustable relatively to each other.

MAXWELL ALPERN.
